C. DUNCAN

ELECTRIC SWITCH MECHANISM

Original Filed Oct. 18, 1919

*Inventor
Charles Duncan*

By
A. Weston Haugh Co.

UNITED STATES PATENT OFFICE.

CHARLES DUNCAN, OF MONTREAL, QUEBEC, CANADA.

ELECTRIC-SWITCH MECHANISM.

Original application filed October 18, 1919, Serial No. 331,711. Patent No. 1,401,891, dated December 27, 1921. Divided and this application filed October 18, 1919. Serial No. 331,710.

To all whom it may concern:

Be it known that I, CHARLES DUNCAN, a subject of the King of Great Britain, and resident of the city of Montreal, in the Province of Quebec and Dominion of Canada, have invented certain new and useful Improvements in Electric-Switch Mechanism, of which the following is a full, clear, and exact description.

- 10 This invention relates to improvements in electric switches, and is a division of the subject matter disclosed in Patent 1,401,891, granted to me on an application filed December 27, 1921.
- 15 The principal object of the present invention is to provide a switch of the tumbler type which may be manufactured and sold at a low cost and which will be durable and efficient in operation.
- 20 A further object is to provide a switch so constructed that the cover may be very easily applied and removed and will not become loosened and fall off in use.

According to the present invention the 25 switch cover is secured to the base by a cross-pin mounted under spring tension. Cams are provided on the cover embracing the pin and holding the cover against accidental disconnection therefrom.

30 In the drawings which illustrate the invention:—

Fig. 1 is a vertical sectional view of a tumbler switch constructed according to this invention.

35 Fig. 2 is a vertical, sectional view at right angles to Figure 1.

Fig. 3 is a top plan view of the switch.

Referring more particularly to the drawings, 11 designates a porcelain base having 40 a centrally disposed, rectangular aperture 12 formed therethrough, above which is a bridge 13 apertured at 14 for the passage of the switch-throw lever. Screw passages 15 are provided in the plane of oscillation of 45 the throw lever as near as possible to the periphery of the base, so that the base is secured in a manner best calculated to withstand the stresses imposed by the operation of the switch. Conductor passages 16 are 50 formed one at each side of the central aperture 12 and entirely clear of all working parts of the switch. These passages are each approximately equidistant between the passages 15. Recesses 18 are provided in the 55 sides of the central aperture 12 to form jour-

nals for the circuit maker, and recesses 19 are formed in the sides of the slot 14 for the reception of the switch lever pivot. A recess 20 is formed around the central aperture 12 at the bottom of the base to receive the back 60 cover.

The terminals 21 and binding posts 22 are secured together and to the switch base by the usual screws having their heads located at the bottom of the base so as to be inaccessible when the switch is in use. These screws are relieved of all bending stresses by the embedding of the terminals and binding posts in the porcelain base and, therefore, have no tendency to loosen. The terminals 70 are located at one end of the central aperture 12 as clearly seen in Figure 1. The circuit maker 24 is a substantially U-shaped member of a size to oscillate freely in the recess 12 and to enter forcibly between the terminals. The extremities 25 of the arms of the circuit maker are outwardly turned to project into the recesses 18 where they act as trunnions supporting the circuit maker. The switch-throw lever 26 occupies the slot 80 14 and projects at one end beyond the base, the end being threaded to receive a ball 27. The opposite end of the lever is bifurcated and each of the bifurcations 28 is connected through an insulator 29 conveniently by 85 hooking or clenching the arms through the insulator. The lever is supported by a pin 30 which passes through it and rests in the recesses 19 of the bridge. A helical spring 31 is connected at one end to the insulator between the bifurcations 28, and is connected at the opposite end to the central part of the circuit maker. It will be noted in Figure 1 that the lever pivot 30 and circuit maker trunnions 25 are both located in the central 90 transverse plane of the switch and that the attachment points of the spring are located in the central transverse planes of the lever and circuit maker.

The bottom of the aperture 12 is closed by 100 a cover plate 32, preferably of insulating material, and the base and bridge are covered by a cover 33 having insulating lining 34.

The pin 30 is U-shaped so that its extremities 35 project above the bridge. These extremities are outwardly turned so as to project beyond the pin receiving recesses 19 of the bridge. The cover 33 is provided with a central aperture 36 at least large enough to permit the cover to be rotated about 110

the U-shaped pin. Diametrically opposite notches 37 are formed in the periphery of the opening 36 to enable the cover to be passed over the out-turned ends 35 of the 5 pin. Bosses or cams 38 are arranged in pairs between the notches 37 and at diametrically opposite points at the edge of the aperture 36. The cams of each pair are spaced apart sufficiently to hold the out-turned pin ends 35 10 securely between them. In order to facilitate the rotation of the cover 33, necessary to attach and release same and also to conceal the porcelain bridge exposed through the cover opening 36, the top of the bridge may be provided with a metal cap 39 having a centrally disposed crown portion 40 which fits freely within the cover opening 36 and forms a central pivot about which the cover will turn 15 easily. This cap is provided with a centrally disposed cruciform opening 41 for the passage of the lever and pin 30. The cap may be attached to the bridge in any suitable manner which will hold it against lateral or rotary motion as by the provision of down-turned 20 lugs 42 engaging recesses or flattened portions of the bridge.

The assembly of the switch is extremely simple. The circuit maker and switch-throw lever carrying the insulator are connected by the spring 31 and dropped into place from the back or bottom of the base. The ball 27 is then screwed onto the end of the lever to retain the parts and the lever drawn up until the pin 30 can be inserted. 30 The spring is now slightly in tension and holds the trunnions 25 of the circuit maker in their recesses 18 and also holds the lever pin 30 in the recesses 19. The cover 33 is then dropped onto the base and rotated until 35 the notches 37 pass the out-turned ends 35 of the pin 30. By the application of slight force the cover may now be rotated and the ends of the pin will ride up out of the notches 37 onto the cover and will subsequently ride up over and drop between the cams 38 so that the cover will be releasably held against rotation.

The operation of the device is extremely simple. The tension of the spring applied 50 to the unsupported end of the circuit maker tends to throw the circuit maker against one end of the aperture 18 and at the same time inclines the lever until the lever and spring axes are in alignment, as clearly shown in 55 Figure 1. The spring being in slight tension holds the parts in this position. To operate the switch the lever is oscillated in the usual manner so that its lower end swings past the pivotal point of the circuit maker. 60 In this action the spring is slightly tensioned until its point of attachment to the lever passes the pivotal point of the circuit maker, whereupon, it exerts a pull on the circuit maker to draw it to the opposite end 65 of the aperture 12.

The spring, in addition to operating the circuit maker, draws down on the lever and holds the extremities 35 of the pivot tightly against the cover 33. It will be noted that these pin extremities 35 are out of parallel 70 with the central portion of the pin being turned toward the cover so that the load of the spring bears only upon the cover and the pin is supported clear of the cap 40 and the porcelain bridge. The result is, that at all times the cover is tightly held and cannot be worked loose by vibration as frequently occurs with the ordinary screwed-on covers. If it is desired to remove the cover it is rotated to force the cams 38 under the pin extremities thereby elongating the spring. 75 After the cams are disengaged from the pin the cover is turned until the pin ends slip into the notches 37, whereupon, the cover may be lifted off. The total rotation either 80 applying or removing the cover is only one-quarter of a revolution so that the cover may be very quickly and easily removed or applied.

While the cover has been shown in connection with a particular base and particular switch construction it will be understood that neither of these are essential to the operation of the cover as the same effect will be produced by the use of a spring actuated pin which is not necessarily the pivot pin of the switch lever. Obviously, many changes in the construction and arrangement of parts may be resorted to without departing from the spirit of the invention or exceeding the scope of the claims, and, therefore, the claims may not be construed as limited to the particular mechanism shown and described.

The advantages of the device are clearly defined and will be readily apparent by any one skilled in the manufacture or installation of such apparatus but for convenience the same are briefly enumerated. The spring is of such type and so arranged that maximum life thereby is ensured. The cover will not become loose and fall off exposing the live parts of the switch, nor will the cover fastening become worn by use and inoperative. The cover may be very easily and quickly removed or applied thus simplifying the work of installation. Fewer assembling operations are required than in the manufacture of ordinary switches and these operations are extremely simple.

Having thus described my invention, what I claim is:—

1. In a switch the combination with a base, of a diametrically disposed member carried thereby, a cover apertured to permit its passage over said member in one position only, said cover being revoluble relatively to the base and member to occupy a position between the base and member whereby it is held to the base.

2. The combination with a device according to claim 1, of a resilient connection extending between said member and the base. 60
3. In combination with a device according to claim 1, a bearing for the cover carried by the base. 65
4. In combination with a device according to claim 1, a bearing for the cover carried by the base having a circular upstanding portion, the cover aperture being circular in part to receive said upstanding bearing portion. 70
5. In combination with a device according to claim 1, means on the cover engageable with said member to releasably hold the cover against revolution. 75
6. A device according to claim 1, in which the cover is provided with a recess to receive an end of said member, whereby the cover is releasably held against revolution. 80
7. In combination with a device according to claim 1, a pair of cams on said cover defining between them a recess for the reception of an end of said member. 85
8. In a switch the combination with a base, of a crowned cap centrally disposed thereon, an elongated member above said cap disposed diametrically of the base and projecting beyond the crowned portion of the cap, and a cover having a central circular aperture for the passage of said crowned cap portion, and radial extensions of said aperture for the passage of said member, said cover being revoluble on the cap into engagement between said member and the cap. 90
9. In combination with a device according to claim 8, cams arranged in pairs on said cover intermediate the radial aperture extensions thereof, the cams of each pair defining between them a recess for the reception of an end of said member whereby the cover is releasably held against revolution. 95
10. A device according to claim 8, in which the cover is recessed to receive an end of said member, whereby the cover is releasably held against revolution. 100
11. A device according to claim 8, in which the member is a U-shaped pin having its extremities outwardly turned to engage the cover and its centre U-shaped portion adapted to pass through the cover aperture. 105
12. In combination with a device according to claim 8, a spring arranged to draw said member and cover against the base. 110
13. In combination with a device according to claim 9, a spring arranged to draw said member and cover against the base and to releasably hold the member in engagement between the cams. 115
14. In combination with a device according to claim 10, a spring arranged to draw said member into the cover recess and to draw the member and cover against the base. 120
15. In combination with a device according to claim 1, a switch operating lever pivoted on said member, and a switch operating spring connected to said lever and operating to draw said member and cover toward the base. 125
16. A device according to claim 15, in which the cover is apertured for passage over said finger in one position and is revoluble on the base for interposition between the base and finger. 130
17. In combination with a device according to claim 16, a cap for the base irreversibly secured thereto forming a bearing for the cover and operating to hold said fingers against revolution with the cover. 135
18. A device according to claim 16, in which the base is recessed to receive a portion of said fingers and hold the same against revolution with the cover. 140
19. In a switch, the combination with a base, of a cover and a finger carried by the base and spring-pressed against the cover to releasably hold the cover to the base, said cover being recessed for the reception of said finger whereby the cover is releasably held against revolution. 145
20. In a switch, the combination of a base, a cover, a finger carried by the base and spring pressed against the cover to hold the cover to the base, and a pair of projections on the cover defining a recess for the reception of said finger whereby the cover is releasably held against revolution. 150
21. A device according to claim 15, in which the cover is interposably between the fingers and base by revolution and is provided with recesses for the reception of said fingers, whereby the cover is releasably held against revolution to disengage it from between the fingers and base. 155
22. A device according to claim 15, in which the cover is movable into engagement between the fingers and base by revolution, and cams arranged in pairs on said cover, the cams of each pair defining between them a recess for the reception of a finger. 160

In witness whereof, I have hereunto set my hand.

CHARLES DUNCAN.
